(57) **CLAIM**

The ornamental design for a combined bird feeder with camera, as shown and described.

DESCRIPTION

FIG. 1 is a front and top perspective view of a combined bird feeder with camera, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged portion view taken from encircled portion labeled, “FIG. 9” in FIG. 1; and,

FIG. 10 is another perspective view thereof, shown in an alternative position.

The even broken lines in the figures illustrate portions of the combined bird feeder with camera that form no part of the claimed design. The dash dot dash lines in FIGS. 1 and 9 are for the purpose of depicting the boundary line of the enlarged view and form no part of the claim.
